UNITED STATES PATENT OFFICE.

JOHN PETERSON, OF FELCH, MICHIGAN, ASSIGNOR OF ONE-HALF TO SWAN J. PETERSON,
OF FOSTER CITY, MICHIGAN.

RAIL-TIE.

1,220,885.

Specification of Letters Patent. Patented Mar. 27, 1917.

Application filed July 11, 1916. Serial No. 108,668.

To all whom it may concern:

Be it known that I, JOHN PETERSON, a citizen of the United States, residing at Felch, in the county of Dickinson and State of Michigan, have invented certain new and useful Improvements in Rail-Ties; and I do hereby declare the following to be a full, clear, and exact description of the invention, such as will enable others skilled in the art to which it appertains to make and use the same.

This invention relates to rail ties of the channeled metallic type, and having wooden seats for the rails, one object of the invention being to improve the construction of the tie by so forming the lower wall thereof that the tie will be prevented from sinking in the road bed beyond a certain point.

Another object of the invention is to admit of any water that enters the interior of the tie escaping past the wooden blocks that form seats for the companion rails.

Other objects will appear and be better understood from that embodiment of my invention of which the following is a specification, reference being had to the accompanying drawing forming a part thereof, in which:

Figure 1 is a top plan view of the rail tie constructed in accordance with my invention, showing the manner of securing one of the rails of the track in operative position thereon,

Fig. 2 is a side elevation of the tie, partly in section,

Fig. 3 is an end view of the tie, and

Fig. 4 is a transverse section, taken through one end of the tie.

Referring to the drawing in detail, the tie is shown as consisting of a channeled elongated body, having a lower or bottom wall 1 and opposite side walls 2, the lower wall 1 being of a greater thickness than the side walls 2, so as to give the lower wall maximum strength, and the side walls 2 are gradually increased in thickness toward their lower edges so as to reinforce the points of juncture between the side walls and the

lower wall of the tie. The under surface of the lower wall 1 of the tie is provided with a longitudinal groove 3, that is of arcuate shape in cross section. By so forming the lower wall of the tie with the groove 3 the material of which the road bed is formed,

will fill the groove or concavity 3 and serve to reduce, to a considerable extent, the sinking of the tie in the road bed.

The opposite ends of the side walls of the tie body are reduced, and the upper edges 60 of the opposite ends of the side walls are formed to provide recesses 4. The recesses 4 on one side wall register with the recesses 4 on the opposite side wall and provide passages for the base flanges of the rails of 65 the track, as shown more particularly in Fig. 4 of the drawing. Each side wall is cut away adjacent the recesses 4 to provide opposed downwardly inclined surfaces 5, and shoulders 6, for a purpose to be here- 70 inafter explained.

Positioned within the tie, and at the opposite ends thereof, are wooden blocks 7 which have their upper surfaces lying above the planes of the lower walls of the recesses 75 4, and formed with seats for the rails, designated 8. The under sides of the blocks 7 are provided with longitudinal grooves 9, which admit of the water that enters the interior of the tie body escaping therefrom. 80

Companion rail clamps 10 are located, respectively, on opposite sides of each of the rails 8 of the track and rest on the inclined surfaces 5 formed in the sides of the tie, and each is provided with a horizontal extension 11, which overlies the upper side of the adjacent block 7 and is secured thereto by means of a bolt 12, which passes through the lower wall 1 of the tie and through the block 7 and the extension 11, and has its 90 upper end threaded for the reception of a nut 13, which is adjustable against the upper side of the extension 11 so as to hold the bolt in operative position. The outer edges of the rail clamping members 10 engage 95 against the shoulders 6, so that any lateral strain or any lateral force exerted on the clamping members 10 by the adjacent rails will be prevented from being distributed to the fastening bolts 12. 100

It is evident that various changes might be resorted to in the construction, form and arrangement of the several parts without departing from the spirit and scope of the invention; hence I do not wish to limit myself strictly to the structure herein described. 105

What I claim as new, is:

A rail tie comprising a hollow body, shoulders formed on the upper edges of the 110

opposite sides of the body, rail-supporting elements positioned within the body and located below the shoulders, rail clamping elements extending across the tie body and engaging the shoulders, extensions formed on the clamping members and extending between the sides of the tie body and resting on and engaging the rail-supporting elements, and fastening means extending

through the extensions and the rail-supporting elements and the lower wall of the tie body. **10**

In testimony whereof I affix my signature in presence of two witnesses.

JOHN PETERSON.

Witnesses:

JOHN DAHLEN,

JOHN KORTEN.
